United States Patent Office

Des. 185,427
Patented June 9, 1959

185,427

CANDELABRA

Thomas P. Duncan, Jr., Warwick, Va.
Application July 10, 1957, Serial No. 46,884

Term of patent 14 years

(Cl. D48—2)

Figure 1 is a side elevational view of a candelabra embodying my new design, and showing in dotted lines a candle for illustrative purposes only; and

I claim:

The ornamental design for a candelabra, as shown and described.
